UNITED STATES PATENT OFFICE.

FRANK E. KINSMAN, OF PLAINFIELD, NEW JERSEY.

ELECTRIC-RAILWAY SYSTEM.

SPECIFICATION forming part of Letters Patent No. 781,431, dated January 31, 1905.

Application filed December 8, 1903. Serial No. 184,268.

To all whom it may concern:

Be it known that I, FRANK E. KINSMAN, a citizen of the United States, and a resident of Plainfield, in the county of Union and State of New Jersey, have invented certain new and useful Improvements in Electric-Railway Systems, of which the following is specification.

This invention relates to an electric-railway system; and the principal object of the invention is to provide a safety system for electric railways, and particularly for third-rail systems, which are used chiefly in large cities and are a constant source of danger because of the exposed character of the working and return conductors. In such systems as ordinarily installed the third rail is close to one of the track-rails, and any person walking on the track must exercise extreme care in order to avoid stepping on the third rail or working conductor and the track-rail which constitutes a part of the return-circuit, and thereby receiving the full working current through the short-circuit formed by his body. Such third-rail systems are chiefly used on elevated structures and are most dangerous at such times, as the line of way may be temporarily blocked because of an accident or otherwise, and the passengers may desire or be compelled to leave the cars or train and make their way along the tracks to the nearest station. At such times especially there is, so far as I am aware, no means now employed for preventing the short-circuiting of the working and return conductors by passengers unfamiliar with the operation of the third-rail systems. The danger of accident is also present whenever an accident occurs not due directly to stepping on the working and return conductors, as is evidenced by the large number of fatalities in recent collisions and other accidents on elevated third-rail systems.

In my system I reduce the danger factor to a minimum by so organizing the system as to make it impossible for a person to form a short circuit by walking on the exposed working conductor or third rail and the track-rail nearest thereto, and I accomplish this by providing a return-path for the current at a point relatively remote from the working conductor or third rail. This return-path may be formed

by any suitable conductor which will constitute with the other elements of the system a complete metallic circuit instead of a circuit having an earth return, as in the systems now in use. I prefer, however, to provide a separate return-feeder electrically connected with that track-rail which is most remote from the third rail, this return-feeder being unconnected with the track-rail adjacent to the third rail. By so organizing the system it will be extremely difficult for any one, even intentionally, to form a short circuit by stepping on the third rail and a track-rail, as no such short circuit will be formed by stepping on the third rail and the track-rail adjacent thereto, and the distance between the third rail and that track-rail which constitutes a part of the return-circuit is so great as to preclude the spanning of the same by any person unless extra efforts to do so are made.

Other features of my invention not hereinbefore referred to will be hereinafter described, and pointed out in the appended claims, and are illustrated in the accompanying drawings, in which—

Figure 1 is a diagrammatic view of an electric-railway system or third-rail system embodying my invention and having a metallic return-conductor. Fig. 2 is a detail illustrating one mode of electrically connecting a return-feeder to one of the track-rails.

Similar characters designate like parts in both the figures of the drawings.

In carrying my invention into effect it should be understood that I may apply it to any existing type of railway system, whether the working conductor be an exposed trolley-wire, a third-rail, a working conductor contained in a conduit, or any other type of conductor for supplying current to a motor on a vehicle traveling on a line of way. I have, however, illustrated the invention in connection with a third-rail system, for the reason that this is the most dangerous so far as the short-circuiting of the same by an individual is concerned.

The track-rails of a line of way are indicated in Fig. 1 by r and r' , and the working conductor or third rail is shown at t . This working conductor or third rail will receive current in the usual manner from outgoing feeders,

one of which is shown at f' leading from a suitable source of supply, such as m , and from this third rail current will be taken by a suitable current-collector, such as s , carried on the vehicle, one axle of which is indicated at 2. From the current-collector or shoe s the current for operating the vehicle will pass through the usual circuit on the vehicle and will leave the vehicle in the usual manner through the 10 axles and wheels thereof. In these diagrams only the field-coils 3 and the armature 4 of the circuit on the vehicle are shown, all of the other elements ordinarily contained in such a circuit being omitted for the sake of simplicity 15 and clearness. It should be understood, however, that this circuit from the current-collector or shoe to the axles and wheels of the vehicle or train may contain any or all of the various devices ordinarily in use in electrically-propelled cars or trains. From the 20 axles of the vehicle the circuit in my present system follows a somewhat different course, even through the wheels, than it does in the ordinary electric-railway system. The reason 25 for this is that only a single track-rail is connected in or forms part of the return-path for the current as it leaves the vehicle. The track-rail which does form part of such return-path is in this case the track-rail r' remote 30 from the third-rail t , and the track-rail r' does not form any part of such return-path, it being divided at suitable intervals by insulation, as shown, into insulated sections, whereas in the usual systems having an earth return the 35 current passes to earth through both track-rails and the system may be short-circuited by stepping on the third-rail and on the rail r . In my improved system, however, it will be seen that a short circuit cannot be established 40 between the rails t and r' and that the life of a passenger or employee will not be in danger unless he bridges the gap between the rails t and r' . These rails are so far apart that it is almost impossible to establish such a short circuit 45 by stepping on these rails. Hence a person walking on an elevated structure or any other embodying a third-rail system in which the third rail is located outside the track-rails will run practically no risk from the high-tension 50 current in such systems. The metallic return-circuit may be established through any suitable return-conductor connected at suitable intervals and by suitable conductors, such as 5, to the track-rail r' remote from the 55 third rail t . This return-feeder c passes directly back to the source of energy or power-house and constitutes, with the outgoing feeder f' , the third-rail t , connected to such outgoing feeder, the traveling current-collector or shoe 60 s , the circuit on the vehicle, and the axles, wheels, and track-rail of that side of the line of way remote from the third-rail t , a complete metallic circuit. Not only is such a system an exceptionally safe one as compared 65 with all other third-rail systems known to me,

but it is also a much more economical system in operation because of the greater conductivity of the metallic return-circuit as compared with the ordinary earth return.

The particular construction and mode of connecting the metallic return conductor or feeder c may be varied within wide limits; but I have shown the return-feeder in Fig. 2 as a copper bar mounted directly on the track-rail r' and connected thereto at suitable intervals by a conductive connection (designated generally by 5) the main element of which may be a screw-bolt 5', preferably having a round head and held in place by a clamp-nut or check-nut, (or both), such as 5", also preferably round, the round head of the bolt and the round nut or nuts having peripheral openings or recesses for receiving a pin to turn the same. This conductive connection 5 is preferably insulated at all points where it is not in contact with the feeder c or with the track-rail r' , the insulating material being so disposed as to constitute an air-tight, and especially a water-tight, casing or seal for preventing electrolysis between the copper and iron or steel elements so connected. This I regard as an important feature of my invention, and I have shown at 6, 7, 8, 9, and 10, respectively, an insulating-washer between the feeder and the track-rail, an insulating-washer between the track-rail and the nut 5", another insulating-washer between the feeder and the head of the connecting-bolt 5', an insulating-cap 9, covering the head of the bolt, and an insulating-cap 10 inclosing the threaded end of the bolt and the nut or nuts thereof, the two caps 9 and 10 being preferably threaded over and into engagement with the washers 7 and 8. Any other suitable means may be employed, however, for conductively connecting the track-rail with the return-feeder and surrounding with an air-tight and water-tight casing the contacting iron and copper surfaces.

What I claim is—

1. The combination with the track-rails of a line of way, one of which rails is divided into insulated sections electrically isolated from the remainder of the system; and with an electrically-propelled vehicle movable along said track-rails, of a working conductor, a source of electric energy, and a return-conductor electrically connected with the other of said track-rails and forming therewith and with said working conductor and the source of energy a metallic circuit.

2. In a railway system embodying track-rails, the combination with an electrically-propelled vehicle movable along said track-rails, of an outgoing feeder, a third rail of large cross-section constituting a working conductor connected therewith, a source of electric energy, and a return-feeder forming with said third rail the outgoing feeder and the source of energy a metallic circuit.

3. The combination with the track-rails of a line of way and with an electrically-propelled vehicle movable therealong, of an outgoing feeder, a third rail connected therewith, a source of electric energy, and a return-feeder electrically connected with one only of said track-rails and forming therewith and with said third rail the outgoing feeder and the source of energy a metallic circuit.

4. The combination with the track-rails of a line of way and with an electrically-propelled vehicle movable therealong, of an outgoing feeder, a third rail connected therewith and located outside one of the rails of the line of way, a source of electric energy, and a return-feeder electrically connected with the other rail only of said line of way and forming therewith and with said third rail the outgoing feeder and the source of energy a metallic circuit.

5. The combination with the track-rails of a line of way and with an electrically-propelled vehicle movable therealong, of an outgoing feeder, a third rail connected therewith and located outside one of the rails of the line of way, a source of electric energy, and a return-feeder electrically connected with the other rail only of said line of way and located outside said rail and forming therewith and with said third rail the outgoing feeder and the source of energy a metallic circuit.

6. The combination with the track-rails of a line of way and with an electrically-propelled vehicle movable therealong, of an outgoing feeder, a third rail connected therewith and located outside one of the rails of the line of way, a current-collector carried by said vehicle and adapted to make traveling contact with said third rail, a source of elec-

tric energy, and a return-feeder electrically connected with the other rail only of said line of way and located outside said rail and forming therewith and with the wheels of the vehicle the current-collector the third rail the outgoing feeder and the source of energy a complete metallic circuit.

7. The combination with the track-rails of a line of way and with an electrically-propelled vehicle movable therealong, of an outgoing feeder, a working conductor connected therewith, a source of electric energy, and a return-feeder supported independently of the outgoing feeder and the working conductor and between the tread and the flange of one of the track-rails and electrically connected with said rail and forming therewith and with said working conductor the outgoing feeder and the source of energy a metallic circuit.

8. The combination with the track-rails of a line of way and with an electrically-propelled vehicle movable therealong, of a power-circuit governing the movement of said vehicle and including a return-feeder supported between the tread and the flange of one of the track-rails and electrically connected to said track-rails by a conductive connector insulated at all points except where it is in electrical connection with the return-feeder and said track-rails.

Signed at New York, in the county of New York and State of New York, this 7th day of December, A. D. 1903.
